UNITED STATES PATENT OFFICE.

JAMES RESSEGIEU, OF CLEOPATRA, MISSOURI, ASSIGNOR OF ONE-FOURTH
TO LEWIS WATSON, OF SAME PLACE.

CORN-PLANTER.

SPECIFICATION forming part of Letters Patent No. 274,382, dated March 20, 1883.

Application filed May 27, 1882. (No model.)

To all whom it may concern:

Be it known that I, JAMES RESSEGIEU, of Cleopatra, in the county of Mercer and State of Missouri, have invented a new and Improved 5 Corn-Planter, of which the following is a full, clear, and exact description.

This invention consists of the combination and arrangement of parts, all as hereinafter described.

10 Reference is to be had to the accompanying drawing, forming part of this specification, in which my improved corn-planter is represented in perspective view.

A represents the sides of a rectangular frame, and B the ends, said frame being mounted on the axle C, near the rear end, and at the front being supported partly by the harrows D, and partly by the counterbalance of the driver upon the seat E, located a little 20 back of the axle C.

The harrows D are attached to the standards F of a cross-bar, G, arranged to shift vertically in the clips H, attached to the front corners of the frame A B, and said cross-bar is 25 connected by rod I with the arm J of a rock-shaft, K, mounted on standards L, and having a lever, M, extending back to the driver's seat, where it is arranged to be set high or low, according to the required set of the harrows, by the lever N and an adjusting-pin, O. The standards F also carry drill-openers P, 30 for making the drills or furrows in which the corn is dropped.

Q represents the seed-hoppers, in each of 35 which is a rotary dropper, R, each having two pockets, S, in which the corn is received from the bottom of the hopper, to be dropped when the pockets pass the opening T below, wherein there is a bottom dropper consisting of the 40 valve V, fixed on pivots W, to be opened by the tappets X on the rotary dropper, and closed by a spring, Y.

The rotary droppers are mounted on the shaft a, which may be worked by the parallel 45 rods b and cranks d, connected to the cranked axle C, or by a check-rope stretched across the

field and around pulleys e f on stud-arms h, and over the sprocket-wheel g on the shaft a of the droppers. When the check-rope is used the connecting-rods b will be detached. 50

The truck-wheels A' are fitted loosely on the axle C, and connected for turning it by clutches i, to be shifted by the hand-lever j at the driver's seat, said lever being suitably connected to the clutches by bars or rods k, as required 55 for that purpose.

The check-row markers consist of the pointed ends m of blocks n, fitted on arms p of the dropper-shaft a, so as to slide toward and from the shaft, and provided with springs q to 60 thrust the points out and cause them to mark in the ground. The springs allow the points to yield when striking a hard substance and pass over it.

In practice the driver's seat will be attached 65 so that it can be shifted along the frame, as may be desired, to adjust it for balancing the machine.

Having thus fully described my invention, I claim as new and desire to secure by Letters 70 Patent—

1. In a corn-planter, the combination, with the frame A B, of the cross-bar G, fitted adjustably in clips H, standards F, harrows D, and the drill-openers P, connected at one end 75 to the said standards, and enlarged and made scoop-shaped at their lower ends, and arranged to work between the wings of the harrows, substantially as shown, and for the purpose set forth. 80

2. In a corn-planter, the combination, with the cross-bar G, fitted adjustably in the frame A B, and carrying the harrows D, of the upright I, the lifting-bar J, shaft K, standards L, lever M, and a triangular or inverted-V-shaped lever, N, capable of adjustment by a key or pin, O, engaging apertures in a leg of the driver's seat E, as set forth. 85

JAMES RESSEGIEU.
